SHEET METAL LUG STRAP SUPPORT

Wingo Herron, Charlotte, N. C.

Application April 12, 1955, Serial No. 500,838

5 Claims. (Cl. 139—154)

This invention relates to supports for holding lug straps of looms to picker sticks, and in particular, an improved lug strap support wherein the parts are adapted to be stamped from sheet metal and wherein the support is frictionally secured in position on a picker stick with an elongated leather strap and a U-bolt and the lug strap is frictionally secured to the support with another leather strap positioned against the outer surface of the support.

The purpose of this invention is to provide a lug strap support for retaining lug straps on picker sticks of looms in which the parts are adapted to be formed of sheet metal instead of castings whereby breakage and damage to the parts are reduced to a minimum.

Conventional lug strap supports, because of the odd design of the parts which normally include an open rectangular shaped frame, are formed by castings or die castings and the extreme shock to which lug strap supports are subjected in use breaks and damages the comparatively thin brittle castings. With this thought in mind, this invention contemplates an improved method of forming a lug strap support whereby substantially all parts thereof are adapted to be stamped from sheet metal and in which the elements are adapted to be readily assembled to form a support.

The object of this invention is, therefore, to provide means for forming a lug strap support in which a lug strap is adapted to be extended around a picker stick and positioned between arcuate flanges of sheet metal elements so that the lug straps may be positively secured in position without danger of sharp edges of the sheet metal elements cutting the straps.

Another object of the invention is to provide an improved sheet metal lug strap support that is adapted to be used in combination with lug straps now in use without changing the lug straps or picker sticks upon which the lug straps are mounted.

Another object of the invention is to provide an improved lug strap support that is adapted to be formed of sheet metal parts in which the parts may readily be assembled by an average mechanic or layman.

A further object of the invention is to provide an improved sheet metal lug strap support which is of a simple and economical construction.

With these and other objects and advantages in view, the invention embodies a base having an elongated bar adapted to be positioned against the face of a picker stick with arms extended from upper and lower portions and with a flange on the upper end, an anchor plate having an arcuate flange on the lower edge adapted to be secured to the inner surface of the base, a base plate having an arcuate flange on the upper edge adapted to be secured to the arms on the lower end of the base, a strap of leather or the like adapted to be positioned between the base and surface of a picker stick, another strap of leather or the like positioned against the face of the base and secured between the anchor plate and upper arms of the base and a U-bolt having nuts and lock washers on extended ends adapted to be positioned around a picker

2

stick and extended through the upper arms of the base and anchor plate.

Other features and advantages of the invention will appear from the following description, taken in connection with the drawing, wherein:

5 Figure 1 is a front elevational view illustrating the improved lug strap support.

Figure 2 is a side elevational view of the lug strap support taken on line 2—2 of Figure 1.

10 Figure 3 is a vertical section through the lug strap support taken on line 3—3 of Figure 1 showing the device positioned upon a picker stick, the picker stick being shown in elevation.

Figure 4 is a sectional plan through the upper part of the device being taken on line 4—4 of Figure 2.

Figure 5 is an exploded view showing the base with the face plate on the lower end and with the anchor plate spaced from the upper end.

20 Figure 6 is a view illustrating a modification wherein the base and face plate are formed integral.

Referring now to the drawing, wherein like reference characters denote corresponding parts, the improved lug strap support of this invention includes a base 10 having upper arms 11 and 12 and a flange 13 at the upper end and lower arms 14 and 15 extended from the lower end, a base plate 16 having an arcuate flange 17 mounted on the arms 14 and 15 at the lower end and an anchor plate 18 having an arcuate flange 19 on the lower edge adapted to be secured to the upper end.

25 30 The anchor plate 18 is secured in position on the upper end of the base with a U-bolt including a U-shaped strap 20 which is provided with threaded studs 21 and 22, the studs extending through openings 23 and 24 in the arms 11 and 12 and also through openings 25 and 26 in the plate 18 and, as shown in Figures 1 and 2, the studs are provided with nuts 27 and lock washers, as indicated by the numeral 28.

35 40 The flange 13 at the upper end of the base extends over the upper edge of the anchor plate 18, as shown in Figure 2, and a cushioning pad or strip, which may be formed of leather or other suitable material, as indicated by the numeral 29, is positioned between the base 10 and the face of a picker stick, such as the stick 30. Another cushioning strip which is also formed of leather or other suitable material and which is indicated by the numeral 31 is positioned between the anchor plate 18 and the base 10. The cushioning strip 31 is positioned to receive a lug strap, as indicated by the numeral 32, and with the lug strap extended around the cushioning material and base severe shocks, strains and stresses to which the lug strap is subjected are taken by the cushioning elements.

45 50 The base 10 is also provided with openings 33 and 34, the sharp edges of which bite into the material of the picker stick or cushioning material against which the base may be positioned providing means for retaining the base in position upon the picker stick.

55 60 The anchor plate 18 is provided with openings 45 and 46 which are in registering relation with the openings 33 and 34 of the base 10, and rivets or other fasteners may be inserted through the openings 45 and 46, and 33 and 34 to secure the anchor plate 18 in position on the base.

65 70 In the design illustrated in Figure 6, the base is formed with an intermediate bar 35, similar to the part 10, with upper arms 36 and 37 and a base 38 having arcuate flanges 39 and 40 extended from upper edges thereof. The ends of the arms 36 and 37 are provided with slots 41 and 42 that are positioned to receive the threaded studs of a U-bolt with the bar 35 positioned against a cushioning element such as the strap 29 and with a lug strap extended around a cushioning element, such as the element 31 with the device positioned upon the edge of a picker

stick. The upper part of the bar 35 may be provided with openings 43 and 44, the sharp edges of which are adapted to bite into the cushioning pad or strip, such as the strip 29 or into the face of a picker stick with the cushioning pad removed.

With the parts designed and assembled in this manner, a base portion, such as the part 10 shown in Figure 5 or the part 35 shown in Figure 6, may be positioned against a cushioning pad on the edge of a picker stick with the upper anchor plate 18 positioned over studs extended from a U-shaped strap, such as the strap 20 and with an additional cushioning pad or leather strip, such as the strip 31, positioned against the opposite face of the base and adapted to extend downwardly, as shown in Figure 2. By this means a lug strap is supported on a 15 picker stick and the lug strap will be retained in position without danger of being damaged by sharp edges of metal parts and the like.

The sheet material, being rolled, is adapted to stand severe shocks, strains and stresses and with the lug strap 20 protected from sharp edges by the cushioning elements the life of the lug strap support of this invention is indefinite.

It will be understood that other modifications, within the scope of the appended claims, may be made in the 25 design and arrangement of the parts without departing from the spirit of the invention.

What is claimed is:

1. A lug strap support comprising a vertically disposed bar having laterally disposed arms on upper and lower ends thereof, a horizontally disposed arcuate flange carried by the lower end of the bar, an anchor plate having an arcuate flange on the lower edge positioned at the upper end of the bar, cushioning elements positioned on both sides of the bar, and a U-bolt having threaded studs extended from the ends adapted to be positioned with the U-shaped intermediate part thereof extended around a picker stick and with threaded ends extended through openings in the upper end of the bar and anchor plate.

2. A lug strap support comprising a vertically disposed sheet metal bar having an extended flange on the upper end, arms extended from edges of the bar and spaced from the upper end and arms extended from the lower end of the bar, a base plate having an arcuate flange on the upper edge carried by the lower end of the bar, cushioning pads positioned on both sides of the bar, an anchor plate having an arcuate flange on the lower edge, and a U-bolt having threaded studs extended through the 45 arms spaced from the upper end of the bar and through 50

the anchor plate for clamping the parts in assembled relation.

3. In a lug strap support, the combination which comprises a bar having transversely disposed arms extended from upper and lower ends providing a base, an arcuate flange extended from the lower end of the base, a complementary arcuate flange carried by an anchor plate spaced from the upper end of the base, cushioning pads positioned on both sides of the bar of the base, and a U-bolt having threaded studs extended through notches in the arms at the upper end of the base and also through holes in the anchor plate said bar having holes therein and said holes positioned in registering relation with holes in the anchor plate through which bolts or other fasteners are inserted for clamping the parts together.

4. In a lug strap support, the combination which comprises a bar having transversely disposed arms extended from upper and lower ends providing a base, an arcuate flange extended from the lower end of the base, a complementary arcuate flange carried by an anchor plate spaced from the upper end of the base, cushioning pads positioned on both sides of the bar of the base, and a U-bolt having threaded studs extended through holes in the arms at the upper end of the base and also through holes in the anchor plate, the upper end of the bar of the base having a flange extended therefrom and said flange at the upper end of the bar being positioned to extend over the upper edge of said anchor plate.

5. In a lug strap support, the combination which comprises a bar having transversely disposed arms extended from upper and lower ends providing a base, an arcuate flange extended from the lower end of the base, a complementary arcuate flange carried by an anchor plate spaced from the upper end of the base, cushioning pads positioned on both sides of the bar of the base, and a U-bolt having threaded studs extended through openings of the arms at the upper end of the base and also through openings of the anchor plate, the upper end of the bar of the base having a flange extended therefrom and said flange at the upper end of the bar being positioned to extend over the upper edge of said anchor plate, and said bar having spaced openings therethrough whereby edges of the openings provide gripping means for retaining the cushioning pads in position upon the base.
